UNITED STATES PATENT OFFICE.

HARRY WALKER, OF OIL CITY, LOUISIANA, ASSIGNOR, BY DIRECT AND MESNE ASSIGNMENTS, TO NATIONAL MANUFACTURING COMPANY OF AMERICA, OF OIL CITY, LOUISIANA, A CORPORATION OF DELAWARE.

COIN-CONTROLLED APPARATUS.

Application filed November 27, 1925. Serial No. 71,816.

This invention relates to an improved coin controlled apparatus which is especially, although not necessarily, designed for use in association with electric player pianos, sound 5 reproducing machines, or other similar coin actuated musical instruments.

My principal aim is to generally improve upon structures of this character by providing one possessing substantially all of the 10 features of known marketed and patented structures, of this class, together with a novel arrangement of details and parts serving to produce a construction which is a decided improvement upon such structures.

15 Briefly, the invention comprises a comparatively small casing forming a housing for an electric switch which is adapted to start and stop an electric motor at predetermined intervals. This switch is preferably of the knife type and the pivoted blade thereof is actuated by a ratchet wheel which is rotatably mounted in the casing adjacent to said blade. The ratchet wheel is rotated in a forward direction by a spring. The 20 wheel is returned, however, through the medium of a novel intermittently operable resetting mechanism. A pivoted spring held dog serves to hold the wheel stationary. In addition to these parts there is a highly 25 practical and exceptionally novel multiple coin actuating device associated with the ratchet wheel in a manner for controlling the degree of forward movement of this wheel, this device being constructed in a manner to accommodate a plurality of 30 different denominations of coins, and the structure being such that it serves to limit the movement of the ratchet wheel so that it is only allowed to travel a distance proportionate to the aggregate value of the coins 35 utilized.

I am aware of the fact that it is not new in a structure of this class to provide a construction which serves to accommodate a 40 plurality of different denominations of coins, and which serves to permit a predetermined number of musical selections to be played so that if a nickel is used, a single selection only is played, if a dime is used, two selections only are played, and so on.

In the improved arrangement herein specifically described, the construction is such

that it allows a reasonable number of different denominations of coins to be utilized in succession, and permits the coins to be inserted rather haphazardly without regard to their value, and permits the playing of a number of selections proportionate to the aggregate value of all of the coins utilized.

More specifically, I provide a structure 55 which allows the switch operating ratchet wheel to turn almost continuously in a forward direction, a distance proportionate to the aggregate value of the coins inserted, regardless of the order of insertion of the 60 coins. I provide, therefore a structure, which permits the playing of a single selection for a single nickel, two selections for a dime, and if desired, six selections for a 65 quarter.

The foregoing is accomplished, as before intimated, by a novel arrangement of details 70 wherein the details themselves are of new construction to insure the provision of a practical, positive, and highly successful apparatus.

The various other features and advantages derived from the new construction, will become apparent from the following 75 description and drawings.

In the accompanying drawings forming a part of this application and in which like numerals are employed to designate like parts throughout the same:—

Figure 1 is a side view of the casing with 80 the cover plate removed as showing the internal structure, the parts being in their normal positions with the electric switch shown open.

Fig. 2 is a horizontal section taken approximately upon the plane of the line 2—2 of Fig. 1, looking downwardly.

Fig. 3 is a fragmentary side elevational view showing one of the parts of the multiple coin controlled device in action.

Fig. 4 is a view very much like Fig. 3 with the portion of the ratchet wheel broken away, with the part of the coin controlled device tripped and one of the details thereof in a further stage in its operation.

Figs. 5, 6 and 7 are similar views of details of the coin controlled device.

Fig. 8 is a reverse side view of the structure shown in Fig. 7.

Fig. 9 is a vertical section taken approximately upon the plane of the line 9—9 of Fig. 1.

Fig. 10 is a view in section and elevation 5 of the spring rotated ratchet wheel.

Fig. 11 is a perspective view of a portion of one of the arms of the coin control device, and

Fig. 12 is a perspective view of a retaining 10 pawl for the ratchet wheel.

In carrying out the invention, I employ a casing 1. This casing may be of any appropriate configuration, the same being indicated as of general rectangular form in the 15 drawing and being open on one side to accommodate a removable closing plate (not shown). As before indicated, there is a special ratchet wheel 2 rotatably mounted in this casing at a predetermined point. Although this ratchet wheel can be constructed 20 otherwise, it is preferably in the form of a metal stamping (see Fig. 10), including a disk having right angularly extending peripheral teeth 3. These teeth are preferably 25 bent to extend somewhat radially with respect to the axis of rotation. Moreover, the teeth are comparatively wide in order to serve a purpose to be hereinafter described.

Removably held against the inner side of 30 the disk of the ratchet wheel is a metal cup 4 in which a flat spring 5 is housed. The spring is anchored upon the hub and disk as shown in Fig. 4 so that it tends to normally rotate the ratchet wheel in a direction from 35 right to left. As plainly evident from Figs. 2 and 9, the disk of the wheel is provided with an outstanding pin 6. This pin is adapted to engage the beveled lower end of a depending part 7 on a pivotally mounted 40 switch blade 8. As before indicated, this blade cooperates with an appropriate socket 9, which, together with the blade forms a substantially conventional knife switch. Both parts 8 and 9 are formed with binding 45 posts 10 and 11 with which electric wires (not shown) are adapted to be connected. These wires are included in a motor circuit. As the device is preferably used in association 50 with an electric player piano, it will be seen that this motor is the one which serves to operate the recording paper roll. To those skilled in the art, it is well known that the record roll travels over a common tracker bar and appropriate means is provided on the 55 roll and bar to control the number of selections to be played. Hence, the motor is intermittently operated thru the action of the switch and the switch is operated according to the amount of money deposited in the apparatus.

Normally, the ratchet wheel is in the position shown in Fig. 1 with the pin engaged with the part 7, thus holding the switch 12 open. A coiled spring 13 controls the switch 60 when it is released. In close cooperative re-

lation with the ratchet wheel is a retaining pawl 14. This is of the construction plainly shown in Fig. 12.

Referring to Fig. 12 it will be seen that it comprises a strip having an especially constructed end portion 15 pivotally mounted upon a pivot pin 16. The strip is disposed vertically, and is provided with a tooth 17 and a stop 18. A spring 19 is connected with the pawl and anchored at a suitable place to 75 normally move the pawl into engagement with the teeth of the ratchet wheel.

As shown more plainly in Fig. 1, the resetting mechanism for returning the ratchet wheel in a direction from left to right to its 80 normal position, comprises a pneumatic in the form of a conventional bellows 20 arranged in the casing and carrying an up-standing bracket 21. This bracket in turn, is provided with a horizontally disposed arm 22 having its free end portion fashioned to engage with the teeth of the ratchet wheel. A suitable spring 23 is connected with the parts 21 and 22 and a stop pin 24 is also provided. An air pipe 25 is connected to the pneumatic. It is obvious that when suction is produced through the pipe 25, the bellows is collapsed moving the upper hinged leaf 85 downwardly and acting to project the arm 22 in a manner to engage it with the ratchet teeth and to impart a rotary thrust to the ratchet wheel. In connection with this reset mechanism, it should be known that the 90 pneumatic device is not an essential feature. Instead, a manually controlled device of 95 suitable design may be utilized.

Disposed inside of the casing adjacent the top are three coin chutes 26, 27 and 28. The coins are adapted to gravitate downwardly through the chutes and into the 100 passageway 29, from where they enter a suitable deposit box, (not shown). It will be noted that the chutes are of different sizes to accommodate different sized coins. In the present instance, I prefer to utilize 105 a nickel, a dime, and quarter as the coin actuating means. In this connection, I might state that a special fraud preventing entrance or depository is used in association with the structure herein shown and 110 described, and this serves to assort and deliver the coins to the proper chute. This fraud preventing device, however, constitutes no part of the present invention, but is made the subject matter of a co-pending 115 application Serial No. 71,815, filed November 29, 1925. As previously indicated, an outstanding feature of the present structure 120 is a novel multiple coin controlled device which serves to control the action of the ratchet wheel. Broadly, this device is constructed in a manner to accommodate a plurality of different denominations of coins, and it embodies a plurality of separate parts which are mounted for inde- 125 130

pendent operation in quick succession and each part limits the movement of the ratchet wheel to a predetermined distance of travel so that when a plurality of coins are inserted in succession into the chute, they will gravitate down through the chute, and actuate these parts in quick succession to allow the ratchet wheel to travel a distance which is measured according to the total value of all of the coins inserted. Specifically, the device comprises three substantially duplicate arms indicated by the reference characters 30, 31, and 32 respectively. These arms are pivoted intermediate their ends upon the pivot pin 33 and the left hand ends of the arms are directed upwardly on an arcuate line and terminate in heads. Also extending upwardly into the depression for the arms are pawl releasing extensions 34.

The end portions of the arm indicated at 35 terminate in what may be designated as coin receiving pockets 36. All of the pockets are of duplicate design. These 25 pockets terminate directly beneath the several coin chutes and operate in guideways formed in the guide member 37 (see Fig. 1). Referring now to the opposite end of the arms, it will be seen that these operate in 30 slots formed in an especial inclined guide bracket indicated generally at 38. Also, mounted on the headed ends of the arm are separate and independent checks 39, 40 and 41, (see Figs. 5, 6 and 7). These checks 35 are somewhat in the form of toothed segments or disks which are pivotally mounted on the headed arm as shown. Each one is provided with an appropriate stop 42. The check carried by the arm 30 is provided 40 with one tooth, the check 40 is provided with two teeth, and the remaining check 41 is provided with six teeth. In this connection it will be noticed that each one of the checks includes a tooth which actually meshes 45 with the teeth of the ratchet wheel during the operation of the device, and also includes what may be designated as an imitation tooth. This also meshes with the teeth of the ratchet wheel, but its function is to 50 literally "kick" the check over to a position to permit it to be readily released from the ratchet wheel to drop, by gravity, down to normal ineffective position. In Fig. 3, this 55 relationship of parts is shown, and in Fig. 4, we see the ratchet wheel engaged with the imitation tooth on the check 39 as it is just about to become disengaged from the ratchet wheel. The first named check 39 cooperates with the nickel chute, the second 60 check 40 with the dime chute, and the remaining check with the quarter chute. The first two checks 39 and 40 serve to over-balance these ends of the arms 30 and 31 and to normally hold the checks disengaged 65 from the ratchet wheel. In fact, these two

checks are themselves weighted so that when not in operation, they assume the position in Figs. 5 and 6. As the check 41 has a greater distance to rotate in its action, gravity alone is not depended upon and a special spiral spring 43 is provided for returning it to its normal position as shown in Fig. 3.

The operation of the device is as follows: Referring to Fig. 1 and assuming that 75 the switch 12 is open, that the ratchet wheel 2 is in its normal position with the pin 6 engaged with the depending part 7 and that the other parts of the device are in the position shown, it will be seen that in order to 80 close the switch, it is necessary for the ratchet wheel to turn in a direction from right to left to disengage the pin 6 from the part 7. This will allow the spring 13 to pull the switch arm downwardly to engage it with 85 the socket 9. Should it be desired to permit the playing of a single selection on the piano roll, a single nickel is inserted and is caused to drop into the chute 26. This will permit the nickel to drop down 90 into the coin receiving pocket 36 carried by the arm 30. The impact and weight of the nickel will swing this arm about the pivot 23 and will bring the check segment 39 into engagement with an adjacent tooth on the 95 ratchet wheel. At the same time, that the check is so engaged with the ratchet wheel, the extension 34 carried by this arm will engage the stop 18 on the retaining pawl 14, thus simultaneously disengaging the pawl 100 for the time being.

With the parts in this relation, the action of the spring for rotating the ratchet wheel will serve to turn the toothed rotatable segment 39 in a direction from right to left. 105 This segment, owing to the stop 42, is only allowed to swing or rotate a very slight distance. With this arrangement, it will be seen that the ratchet wheel will be limited in its movement so that it rotates a single step 110 or a distance of one tooth. Now, in order that the switch may be again opened after the single selection has been played, it will be necessary that the resetting mechanism come into play. This is done by the vacuum created in the pneumatic bellows 20. Under this suction, the leaf will be swung downwardly and through the medium of the parts 21 and 22, the ratchet wheel is 115 returned to its initial position, at which time the pin 6 moves the blade 8 of the switch up and opens the switch 10. As the check 40 is provided with two teeth instead of a single tooth like check 39, it will be seen that this contrivance moves substantially twice as far as the check 39. Obviously, then, if a dime is dropped into the chute 27, the ratchet wheel will be allowed to travel two steps or two teeth and it 120 will thereby require two operations of the 125

intermittent reset mechanism to return the ratchet wheel. In this way, two selections may be had for a dime. The remaining check is formed with six teeth so that by inserting a quarter into the remaining chute and operating the arm 32, and its respective segment or check, the ratchet wheel will be allowed to travel six steps, thereby giving six selections for a quarter. By multiplying this structure, coins of additional denominations might be accommodated, but it is believed that the three coins mentioned will suffice for a commercially successful device.

It is plainly apparent from the foregoing that the structure is substantially automatic in operation, for as each coin is dropped through its respective chute, it operates on the part of the multiple coin support device to allow the ratchet to travel a distance proportionate to the value of that particular coin. The outstanding advantage of the arrangement is that it is not necessary to operate the reset mechanism after insertion of a single coin. Instead, one may insert a nickel in the nickel slot, a dime in the dime slot in quick succession, and a quarter in the quarter slot. Therefore, instead of obtaining only six selections, nine selections will be played. Attention is directed to the fact that with the mechanism described, the operation is positive and only a single impact is required to operate each part of the coin controlled device. It is not necessary to insert coins in any orderly fashion according to their denominations. The quarter might be dropped first, the dime second, and the nickel third, or in any order. At the same time the proper number of selections will be automatically played according to the aggregate amount of money inserted. Not only this, under the arrangement specified, the ratchet wheel travels substantially and continuously in the direction from right to left. It travels one tooth for a nickel, two teeth for a dime, and six teeth for a quarter. Thus, instead of the switch continuously opening and closing such as is the case with known devices of this kind, the switch opens when the first nickel is inserted and stays open until all of the money has been utilized in playing of proper number of selections.

These and other advantages and features of the invention will no doubt be plain to those skilled in the art to which the invention relates. Moreover the accuracy and practicability of a structure of this kind will be appreciated by such persons. In view of this, a more lengthy description of the invention is thought unnecessary.

While the preferred embodiment of the invention has been shown and described, it is to be understood that minor changes coming within the field of invention claimed may be resorted to if desired.

Having thus described the invention, what I claim as new is:-

1. In a device of the class described, in combination, a spring rotated ratchet-wheel adapted to rotate in a forward direction, a holding dog for said wheel, an electric circuit closing switch, means carried by the wheel for operating the switch at predetermined intervals, an intermittently operated resetting mechanism for returning the ratchet-wheel to a normal position at a predetermined time, and a multiple coin actuated device for controlling the degree of forward movement of the ratchet wheel, said device being constructed in a manner to accommodate and receive a plurality of different denominations of coins in succession, whereby said ratchet wheel is allowed to turn almost continuously a distance proportionate to the aggregate value of coins utilized.

2. In a device of the class described, in combination, a spring rotated ratchet-wheel adapted to rotate in a forward direction, a holding dog for said wheel, an electric circuit closing switch, means carried by the wheel for operating the switch at predetermined intervals, an intermittently operated resetting mechanism for returning the ratchet-wheel to a normal position at a predetermined time, and a multiple coin actuated device for controlling the degree of forward movement of the ratchet wheel, said device being constructed in a manner to accommodate and receive a plurality of different denominations of coins in succession, whereby said ratchet wheel is allowed to turn almost continuously a distance proportionate to the aggregate value of coins utilized.

3. In a device of the class described, in combination, a spring rotated ratchet wheel adapted to rotate in a forward direction, a retaining dog for said wheel, an electric circuit closing switch, means carried by the wheel for operating the switch at predetermined intervals, an intermittently operated resetting mechanism for returning the ratchet wheel in a step-by-step manner to a normal position at a predetermined time, and a multiple coin actuated device for controlling the degree of forward movement of the ratchet wheel, said device being provided with a plurality of independent coin chutes for predetermined sizes of coins, and also including a plurality of separate parts mounted for independent operation in quick succession, said parts cooperating with said chutes and with said ratchet wheel for limiting the rotation of the latter a predetermined distance upon operation of each part, where-

by to permit said ratchet wheel to turn a distance proportionate to the aggregate value of coins utilized.

4. In a structure of the class described, in combination, a casing, a plurality of individual coin chutes carried by said casing and adapted for reception of different sizes of coins, a knife-switch in said casing, a rotatably mounted ratchet wheel mounted in the 10 casing adjacent the swingable blade of the switch, said wheel being provided with a pin for opening said switch, means for rotating the ratchet wheel in a forward direction, a retaining pawl cooperable with the wheel for 15 holding it in a set position, an intermittently operable resetting mechanism for returning the ratchet wheel to a normal position, and a plurality of coin actuated members pivotally mounted in the casing adjacent said 20 ratchet wheel for independent operation, said members being provided with coin receiving seats located in alignment with said chutes, and being further provided with means cooperable with the ratchet wheel for 25 limiting the degree of forward rotation thereof.

5. In a device of the class described, in combination, a casing, a plurality of coin chutes of various sizes located in said casing, 30 an electric switch in the casing, a rotatably mounted ratchet wheel including a spring for rotating it in a forward direction, a spring pressed pawl cooperable with the ratchet wheel for maintaining it normally 35 stationary, an intermittently operable resetting mechanism for returning the ratchet wheel in a step-by-step manner to a normal switch opening position, and a multiple coin actuated device in said casing, said device 40 comprising a plurality of arms pivotally mounted between their ends in said casing, the arms being formed at one end with coin receiving pockets located in alignment with 45 said chutes, being provided at their opposite ends with means cooperable with the teeth of the ratchet wheel for limiting the degree of rotation of the latter in a forward direction, and being provided between their 50 ends with release means cooperable with said pawl.

6. In a structure of the class described, a special ratchet wheel for use in association with a check controlled apparatus of the kind specified, said ratchet wheel comprising 55 a hub portion constructed to formulate a spring housing, and a toothed peripheral portion, the teeth being comparatively long, disposed parallel to the axis of rotation, and being adapted to accommodate a plurality 60 of coin actuated check elements.

7. In a structure of the class described, a rotatably mounted ratchet wheel, a retaining pawl cooperable with the teeth of the wheel, said pawl being provided with an angular extension, a pivotally mounted arm, a

pivotaly mounted check carried by one end of the arm and cooperable with the teeth of the ratchet, a coin pocket on the opposite end of the arm, and a release extension carried by the intermediate portion of the arm and cooperable with the aforesaid extension. 70

8. In a structure of the class described, in combination, a rotatably mounted ratchet wheel provided with right angularly extending comparatively long teeth, a plurality of pivotally mounted arms disposed in side-by-side relation adjacent said ratchet wheel, and check elements carried by corresponding ends of the arms, and capable of being brought into operative engagement with the 75 teeth of the ratchet wheel.

9. In a structure of the class described, a multiple coin actuated device adapted for co-operation with a single toothed ratchet wheel, said device embodying an arm pivotally mounted between its ends, a toothed segment on one end of the arm cooperable with the teeth of the ratchet, a coin pocket on the opposite end of the arm, and an upstanding releasing extension on the intermediate portion of the arm. 80

10. In an apparatus of the class described, a casing, a knife switch in the casing, a rotatably mounted ratchet wheel in the casing located adjacent said switch and provided with a switch controlling pin, a spring cooperable with the ratchet wheel for rotating it in one direction, a pivotally mounted spring pressed pawl cooperable with the ratchet wheel for holding it in a set position, 95 a plurality of different sized chutes located adjacent the pawl, a resetting mechanism separate and independent from the pawl and cooperable with the latter, and a multiple coin actuated device cooperable with the ratchet wheel for limiting the degree of movement in one direction and for simultaneously disengaging said pawl. 100

11. In a coin controlled apparatus of the character designed, a make and break device adapted to control an electric circuit, an element movable step by step in opposite directions to and from a predetermined position, said element being normally positioned to break the circuits in said predetermined position, means for automatically moving said element in one of said directions, coin tripped means for checking the element in said one direction, said last means being constructed to accommodate a plurality of different denominations of coins in succession, whereby said element is allowed to move in said one direction a distance proportionate to the aggregate value of coins utilized, and means for returning said element to circuit 110 breaking position after a predetermined uninterrupted period of circuit activity. 120

12. In a coin controlled apparatus of the character defined, a make and break device adapted to control an electric circuit, an ele- 130

ment movable step-by-step in opposite directions to and from circuit closing position, a member carried by said element and cooperable with said make and break device to actuate the latter to open the circuit in a predetermined position beyond said circuit closing position, said element being normally positioned to break the circuit in said predetermined position, means for automatically moving said element in one of said directions, coin tripped means for checking the movement of the element in said one direction, said

coin tripping means embodying a plurality of separate coin actuated parts constructed in a manner to receive a plurality of different denominations of coins in succession in order to allow said element to move substantially uninterruptedly in said one direction a distance proportionate to the aggregate value of coins utilized, and mechanism for returning said element in a step by step manner to said predetermined position.

In testimony whereof I affix my signature.
HARRY WALKER.
